[57] CLAIM

The ornamental design for a display rack unit for perfume vials, packages and the like, as shown and described.

DESCRIPTION

FIG. 1 is a perspective view of a display rack unit for perfume vials, packages and the like, showing my new design;

FIG. 2 is a top plan view thereof;

FIG. 3 is a front elevational view, the rear being a mirror image thereof;

FIG. 4 is a left side elevational view thereof;

FIG. 5 is a right side elevational view thereof; and,

FIG. 6 is a bottom plan view thereof.

FIGS. 2-6 have been shown on a reduced scale with respect to FIG. 1.

FIG. 1

FIG. 5

FIG. 2

FIG. 3

FIG. 6

FIG. 4
